(21) Appl. No.: **29/724,346**

CLAIM

(22) Filed: **Feb. 14, 2020**

The ornamental design for a display screen or portion thereof with transitional graphical user interface, as shown and described.

Related U.S. Application Data

(63) Continuation of application No. 29/663,015, filed on Sep. 11, 2018, now Pat. No. Des. 876,477.

DESCRIPTION

(51) **LOC (13) Cl.** **14-04**

FIG. 1 is the first image in a sequence of a display screen or portion thereof with transitional graphical user interface showing our new design;

(52) **U.S. Cl.**

FIG. 2 is the second image thereof;

USPC **D14/488**

FIG. 3 is the third image thereof;

(58) **Field of Classification Search**

FIG. 4 is the fourth image thereof;

USPC D14/485-95; D22/112

FIG. 5 is the fifth image thereof;

CPC .. G06F 3/0481; G06F 3/0482; G06F 3/04812;

FIG. 6 is the sixth image thereof;

G06F 3/04817; G06F 3/0484; G06F

FIG. 7 is the seventh image thereof; and,

3/0485; G06F 3/048; G06F 3/0487; G06F

FIG. 8 is the eighth image thereof.

3/0488; G06F 3/04883; G06F 3/04886;

The dashed broken line perimeter in the drawings illustrates a display screen or portion thereof and forms no part of the claimed design. The remaining dashed broken lines in the drawings illustrate portions of the graphical user interface that form no part of the claimed design.

G06F 3/0489

The appearance of the transitional image sequentially transitions between the images shown in FIGS. 1-8. This process or period forms no part of the claimed design.

See application file for complete search history.
